UNITED STATES PATENT OFFICE.

JAMES LOCKE ERWIN, OF BURLINGTON, NORTH CAROLINA.

FOLDING PEDESTAL.

SPECIFICATION forming part of Letters Patent No. 608,659, dated August 9, 1898.

Application filed November 14, 1896. Serial No. 612,076. (No model.)

To all whom it may concern:

Be it known that I, JAMES LOCKE ERWIN, a citizen of the United States, residing at Burlington, in the county of Alamance and State 5 of North Carolina, have invented a certain new and useful Improvement in Folding Pedestals, of which the following is a full, clear, and exact description.

This invention relates to a folding pedestal 10 or stand for the use of undertakers in supporting burial-caskets and for other uses and purposes.

The object of the invention is to provide a pedestal which may be folded into small compass 15 and which when opened and arranged for use will be perfectly firm and absolutely safe against accidental displacement of its members.

The invention consists of two frames, each 20 composed of uprights connected by top and bottom cross-bars and supplied with suitable feet, the cross-bars being provided with gains or mortises, and a vertical connecting-rod, whereby the said frames may be folded along- 25 side of one another and also may be interlocked at right angles to one another, the said frames in this last-named interlocked position being otherwise and additionally locked together, so as to insure against accidental 30 displacement, all as I will proceed now more particularly to set forth and finally claim.

In the accompanying drawings, illustrating 35 my invention, in the several figures of which like parts are similarly designated, Figure 1 is a perspective view of the pedestal folded. Fig. 2 is a perspective view of the pedestal arranged for use. Fig. 3 is a sectional elevation. Fig. 4 is a top plan view of the folded pedestal. Fig. 5 is an enlarged sectional 40 view of the upper interlocking joint.

Without thereby limiting my invention to the use of any particular material for the construction of my pedestal I will describe the invention as constructed of wood and metal. 45 There are two frames of similar construction, and each frame is composed of uprights *a a*, which are connected by the cross-bars *b c*. The uprights and cross-bars may be further bound together by ornamental metal straps *d* 50 and the ornamental metal braces *e*. The uprights may be provided with any suitable ornamental feet *f*.

The cross-bars *b* and *c* of one frame are provided with the gains or mortises *g* in their upper surfaces, and the cross-bars *b* and *c* of the other frame are provided with the gains or mortises *h* in their lower-surfaces, and these gains or mortises are cut to one-half the depth of the cross-bars, so that when the said cross-bars are fitted together at right angles the upper surfaces of the said cross-bars will be perfectly flat and level. The gains or mortises are of such shape and so disposed as to provide for the interlocking of the cross-bars at right angles, and the frames are so arranged with relation to one another that one frame 55 may be lifted clear of the other and be swung around into a plane nearly parallel with the length of the cross-bars of the other, as shown, respectively, in Figs. 2 and 1.

In order to provide for the permanent engagement or union of one frame with the other, I pass a vertical connecting-rod *i* centrally through the cross-bars of the two frames, and this rod is enough longer than the distance between the two cross-bars of any one frame to permit of the lifting of one frame clear of the other for purposes of folding, the additional length of said rod being disposed below the lower cross-bars. By connecting the upper and the lower cross-bars by means of this single connecting-rod *i* the alignment of the frames is always preserved and the engagement of the gains or mortises 60 always insured.

When the cross-bars are made of wood, it will be desirable to line or reinforce the gains with metal plates *k*.

While the frames when arranged at right angles, as in Fig. 2, interlock and while such interlocking may be sufficient with careful handling, still in order to insure the stability of the pedestal and to preclude the possibility of the movement of the thus-interlocked frames one upon the other, as by a person 90 jostling them or against the casket supported upon the pedestals, I prefer to use means for additionally locking the cross-bars together, and for this purpose I provide one of the upper cross-bars with any suitable latch or lock which will automatically or otherwise positively lock the said two frames together when they are arranged at right angles to one another, as in Fig. 2. I have shown one form 95 100

of such lock, and, as illustrated in detail in Figs. 3 and 5, it consists of a lever *l*, arranged in a mortise in one of the cross-bars and pivoted at *l* and provided with a thumb-piece *l'*, 5 projecting into a countersink in the face of the upper cross-bar and having a nose *l''*, which is adapted to engage a keeper *m* on the other cross-bar. This lever is normally sprung to engage the said keeper by means 10 of a spring *n*, and the nose is so beveled that as the cross-bar of one frame is dropped into the gain of the cross-bar of the other frame the lever will be retracted to permit the said cross-bar to drop into interlocking position 15 with the other cross-bar and then will spring into engagement with the keeper *m*. The frames may be released by depressing the lever by pressure on its thumb-piece *l'*.

I am aware that it is not new with me to 20 provide folding pedestals for the support of caskets and other objects and that heretofore such pedestals have been supported in condition for use by means of interlocking devices, and I am also aware that such folding 25 pedestals have been provided with a locking device; but I am not aware that prior to my invention any such pedestal has been constructed, as is mine, to interlock automatically when arranged for use and in addition to such 30 interlocking capacity inherent in its construction has been provided with an auxiliary locking device which may not be displaced by the canting or tilting of one frame upon the other, and I esteem it of the utmost importance that 35 a folding pedestal should have its members locked against the peradventure of displacement when in use for obvious reasons.

What I claim is—

1. A folding pedestal, consisting of two 40 frames each composed of uprights and cross-bars connecting the said uprights at their tops and near their bottoms, the said cross-bars being provided with matching gains or mortises, and a central rod passed through 45 the several cross-bars of the two frames, pivotally connecting them and of greater length than the distance between the said cross-bars,

so as to permit the said frames to be lifted one out of the other for folding purposes, substantially as described. 50

2. A folding pedestal, consisting of two frames, each composed of uprights, and cross-bars connecting the said uprights at their tops and near their bottoms, the cross-bars having interlocking gains or mortises, and a 55 central connecting-rod, combined with an additional and positively-acting locking device for engaging the interlocked frames and securing them against accidental displacement, substantially as described. 60

3. A folding pedestal, consisting of similar frames composed of uprights and pairs of cross-bars connecting them at their upper and near their lower ends, a central rod pivotally connecting the said frames through 65 their cross-bars, the said cross-bars having interlocking gains or mortises, and an auxiliary locking device operating automatically to permit the engagement of the gains or mortises of the respective cross-bars and to positively lock the said cross-bars and consequently the frames when the gains or mortises are so engaged, substantially as described. 70

4. A folding pedestal, consisting of two 75 similar frames, each composed of uprights, and cross-bars connecting such uprights at their tops and near their bottoms, and provided with matching gains or mortises, the said frames being pivotally united and adapted to be separated for folding purposes, and to be interlocked by means of the gains or mortises for purposes of use, combined with an auxiliary locking device arranged in the cross-bar of one of the frames and positively 80 engaging the cross-bar of the other frame, substantially as described. 85

In testimony whereof I have hereunto set my hand this 13th day of November, A. D. 1890.

JAMES LOCKE ERWIN.
